UNITED STATES PATENT OFFICE.

EDGAR D. CHURCH AND JACKSON W. VAN BRUNT, OF SAGINAW, MICHIGAN, ASSIGNORS TO JACKSON & CHURCH COMPANY, OF SAGINAW, MICHIGAN, A CORPORATION OF MICHIGAN.

LATCH.

Application filed September 24, 1923. Serial No. 664,616.

To all whom it may concern:

Be it known that we, EDGAR D. CHURCH and JACKSON W. VAN BRUNT, citizens of the United States, both residing at Saginaw, in the county of Saginaw and State of Michigan, have invented certain new and useful Improvements in Latches; and we do hereby declare the following to be a full, clear, and exact description of the invention, such as will enable others skilled in the art to which it appertains to make and use the same.

This invention is a latch for use on the intermittently rotatable platen-actuating spiders of brick presses and for other services that require the use of a sliding spring-pressed bar having a projecting end that acts as a detent to engage a stop provided on the heavy wheel or disk which is to be rotated by the detent. The bolt of such a latch is usually spring-pressed outwardly and its outer end normally slides upon a way or track usually circular, having abrupt ended cams that form stops at suitable intervals. The outer end of the spring-pressed bar rides over this cam surface to its end and upon running off the end of the cam is forcibly projected outward by the action of the spring. A side of the latch thereupon takes against the end of the cam, enabling the intermittently rotatable spider to propel the platen of the press into its next set position.

Such an intermittent grip device is commonly employed on the oscillating spiders that operate the intermittently movable platens of sand and lime brick presses and the like.

In practice the bolts or dogs of latches that are subjected to the heavy strains incident to this class of service frequently break, temporarily putting a brick machine out of commission. It has been found that much of the breakage is due to the fact that when the spring-pressed bolt of the latch rides off the end of the cam it is shot forcibly outward, striking the face of the annular track that carries the cams. When the end of the bolt repeatedly strikes the face of the track in the manner noted, the bolt eventually becomes crystallized and breaks, and a depression is battered into the face of the cam track, causing the machine to become very noisy and often necessitating replacement of the track. The

bolt spring also sometimes crystallizes and breaks from this repeated jarring.

Our invention has for its objects, first, to provide on the bolt itself a removable stop and on a wall of the channel in which the bolt slides a coacting bumper made of cushioning material to receive the impact of the bolt and thus prevent the extremity of the bolt striking the face of the track.

A further object is to so shape the end of the cam and the end of the bolt as to reduce the abruptness with which the bolt runs off the end of the cam, consequently reducing the amount of jar or impact.

With the foregoing and certain other objects in view which will appear later in the specifications our invention comprises the devices described and claimed and the equivalents thereof.

In the drawings Fig. 1 is a view of the latch applied to the rim of a spider of a brick machine, the latch cover removed.

Fig. 2 is a section on the line 2—2 of Fig. 1, the cover in place.

Fig. 3 shows the inner face of the latch cover.

Fig. 4 is an end view of the cover as viewed from 4—4 of Fig. 3.

1 is the bolt or dog mounted in a suitable recess or channel formed in the latch lug 2 on the rim 3 of a brick machine spider.

At 4 is indicated by dotted lines the cam and cam track on a gear to be intermittently rotated by the latch, as is common in brick machines and the like.

In a face of the bolt 1 is formed a recess, and removably secured therein is the stop 5 that projects beyond the face of the bolt 1. The stop 5 is preferably made of hardened steel or equivalent material.

A bumper 6 of hard fibre or other suitable material is removably bolted to the inner face of the removable latch cover 7, a suitable recess being formed in the face of the cover to receive the bumper 6 which is backed or reinforced by a shoulder 8 on the cover. When the cover 7 is secured in place on the rim 3 as shown in Fig. 2 the fibre bumper 6 receives the impact of the stop 5 as on a cushion when the end of the bolt runs off the face of the cam, as indicated in Fig. 1.

The impact of the bolt is thereby transmitted to the spider 3 and the end of the bolt is prevented from striking the cam-

track face of gear 4. Battering of the track and crystallization of the spring and of bolt 1 are thereby avoided.

The sides 9 of the channel in which the bolt 1 moves back and forth are preferably made of considerable thickness as shown in Fig. 1, so that the lateral strain on the side of the bolt is properly transmitted to the rim 3 of the spider.

To prevent the end of the bolt from being projected too suddenly when the extremity of the cam 11 is reached we prefer to round the corner 10 of the cam and to bevel the working face of bolt 1 as shown 15 at 13 in Fig. 1.

By the means above described we have produced a simple, durable and relatively inexpensive latch especially suited to the hard service required for example in operating the intermittent platens of brick machines or the like. Noise is reduced, crystallization of the latch and latch spring is 20

prevented, and by mounting one of the stop members, such as the cushioning bumper 6, upon the removable cover 7 repairs or renewals of either the bumper 6 or stop 5 can be made easily and quickly. 25

Having thus described our invention, what we claim and desire to secure by Letters Patent is:

In a latch of the class described, a spring-pressed longitudinally disposed bolt, a removable stop member secured to a face of said bolt, a removable cover for said latch, a bumper of softer material than the said stop member removably secured to the inner face of said cover and adapted to receive the impact of said stop-member for the purposes set forth. 35

In testimony whereof, we affix our signatures. 40

EDGAR D. CHURCH.
JACKSON W. VAN BRUNT.
